(57) **CLAIM**

The ornamental design for a door swing limiter, as shown and described.

DESCRIPTION

FIG. 1 is a perspective view of a door swing limiter; FIG. 2 is a front view of the door swing limiter thereof; FIG. 3 is a rear view of the door swing limiter thereof; FIG. 4 is a right view of the door swing limiter thereof; FIG. 5 is a left view of the door swing limiter thereof; FIG. 6 is a top view of the door swing limiter thereof; and, FIG. 7 is a bottom view of the door swing limiter thereof. In the drawings, the broken lines depict unclaimed portions of the design only and form no part of the claimed design.

1 Claim, 4 Drawing Sheets
